Primary Examiner — Mary Ann Calabrese*Assistant Examiner* — Natalya M Rapundalo(74) *Attorney, Agent, or Firm* — Winthrop & Weinstine, P.A.(57) **CLAIM**

The ornamental design for a pour over brewing device, as shown and described.

DESCRIPTION

FIG. 1 is a front view of the pour over brewing device in accordance with the present disclosure;

FIG. 2 is a left side view thereof;

FIG. 3 is a right side view thereof;

FIG. 4 is a rear view thereof;

FIG. 5 is a top view thereof;

FIG. 6 is a bottom view thereof; and,

FIG. 7 is a top, isometric view thereof.

The broken lines in the drawings represent portions of the pour over brewing device and form no part of the claimed design.
